UNITED STATES PATENT OFFICE

GEORGE B. PICKOP, OF NEW HAVEN, CONNECTICUT, ASSIGNOR TO MALLEABLE IRON FITTINGS COMPANY, OF BRANFORD, CONNECTICUT

VIBRATOR

Application filed October 4, 1927. Serial No. 223,979.

This invention relates to vibrators, and more especially to that type of vibrators operated by a motive fluid, such as compressed air, and comprising a shell or casing having a cylinder within which is mounted a vibrator piston striking against the heads of the cylinder. The use of such vibrators has increased materially in recent years owing to the fact that such a device has been found 5 adaptable to shaking, jarring or rapping operations of many different kinds. One of its largest uses, however, is in the foundry where it is used in connection with sand riddling operations, flask rapping and pot 10 rapping operations, and also in shaking the cores out of castings, especially those of larger sizes.

It has been common in the past to provide such vibrators with attaching ends, which 20 may be bolted to the devices within which the vibrator is used, and in some instances, the vibrator has been made a part of a hook which can be attached to foundry flasks or the like.

25 I have found it very desirable, however, to provide the vibrator body itself with an attaching end which may be readily coupled with a foundry flask, pot or casting, by being merely hooked over a part thereof, which 30 connection not only transmits the vibrations efficiently to the article upon which the work is adapted to be done, but which also provides for an easy removal of the vibrator when the work is done.

35 In connecting the vibrator in various relations, it has been found that one kind of an attaching head or hook is not the most efficient in all cases, and I have proposed, therefore, to provide an attaching 40 head upon each end of the vibrator, one being adapted for use with certain objects, and the other being more suitable for use in other relations. Such an arrangement not only provides an instrument of wider use 45 than if only one attaching head were provided, and, therefore, not only permits one vibrator to accomplish the work of two, but it prevents duplication in equipment and will often, particularly when the two attaching 50 heads are duplicates, prevent a cessation of

the work owing to the breaking of one of the heads.

These vibrators are often made in very large sizes, the pistons sometimes being as much as six to eight inches in diameter, and as they are very heavy it is advantageous to provide means of suspending them from a traveling crane or the like, so that they may be readily transported from one place to another.

One object of my invention, therefore, is to provide a vibrator having attaching ends upon the heads thereof, the ends being so constructed that they may be readily attached to and removed from various devices to be 60 operated upon, and when so attached will efficiently transmit vibrations thereto.

Another object of my invention is to provide a vibrator of the type described with attaching heads of different character so as 70 to adapt the same vibrator to various uses, and thereby prevent duplication in equipment and enlarge the scope of uses to which the instrument may be put.

Other objects of the invention consist in 75 providing a vibrator wherein the heads of the vibrator themselves are provided with attaching devices, so that the latter become a unitary part of the instrument, and to provide means by which the vibrator may be suspended and readily transported from place to place by power operated devices to facilitate its use.

A still further object of the invention is the provision of a double ended vibrator having attaching ends of such character that when these ends are coupled to or hooked over the device to be vibrated, the weight of the vibrator is supported by the device itself, so that the jar of the vibrations will be transmitted entirely to this device.

To these and other ends, the invention consists in the novel features and combinations of parts to be hereinafter described and claimed.

In the accompanying drawings:

Fig. 1 is a perspective view of a vibrator, embodying my invention;

Fig. 2 is a side elevational view of the same;

Fig. 3 is a top plan view of the vibrator; Figs. 4 and 5 are left and right hand end views respectively of the device as shown in Fig. 3.

As an illustration of a preferred embodiment of my invention, I have shown a vibrator body 10, having heads 11 and 12, at opposite ends thereof. It will be understood that the vibrator body 10 is provided with a cylindrical chamber within which is mounted a reciprocating piston 10^a, shown in dotted lines in Fig. 2, which acts upon both heads 11 and 12.

The head 12 is provided, in this instance, with an integrally formed attaching end in the form of a jaw 13, provided with an opening 14 to permit it to be hooked over the edge of a flask or pot, or a part of a casting to be vibrated. As will be apparent when the jaw 13 is hooked over the edge of a flask, for example, the weight of the vibrator will tend to tilt the latter about the flask edge so that the shoulder 15 will firmly abut against the side of the flask while firm contact will likewise be effected between the upper edge of the flask and the corner 16 of the jaw. While, as will be hereinafter explained, the vibrator is provided with means by which it may be suspended from a crane hook or the like, by a chain, for transportation from one place to another, it is not intended to be so suspended during its operation, as a more efficient result will be obtained when the weight of the vibrator is carried by the article itself, as this weight not only tends to make a firm contact between the vibrator and the article, but also none of the vibration is lost in the suspending means.

The opposite head 11 of the vibrator is also provided with an attaching jaw 17, but one of a different type. This jaw is provided with an opening 18, the lower side 19 thereof having a V-shaped formation 20, which will be found useful in receiving and hooking over such articles as lathe bed castings or the like, for shaking the cores out of such castings.

Between the heads 11 and 12 is mounted the vibrator body 10, which is secured in place by a number of bolts 21, passed through openings in the heads and receiving nuts on their protruding ends. Also connecting the two heads is a bail or the like 22, provided with an opening 23 whereby the vibrator may be supported by a chain or cable and moved from place to place. At each end the bail is provided with spaced eyes 26 which receive the ends of certain of the bolts 21 to secure the bail firmly to the vibrator.

In Fig. 1 of the drawings I have shown a hook 24, received in the opening 23, and supported by a chain 25, which may be carried by a traveling crane or the like. In this figure, the jaw 13 is shown engaged with a boiler casting for knocking the core out of the latter, and it will be apparent that the

weight of the vibrator is supported by the casting so that none of the effect of the vibrations of the piston will be lost in the links of the chain 25 or in the connection between the hook 24 and the opening 23.

By providing a vibrator between a pair of attaching jaws in this manner the scope of use of the device is widened, as one instrument may be used in a number of relations, and moreover, when the jaws are similar, if one becomes broken the vibrator may be turned end for end, and the other used.

While I have shown and described a preferred embodiment of my invention, it is to be understood that it is not to be limited to all of the details shown, but is capable of modification and variation within the spirit of the invention and the scope of the appended claims.

What I claim is:

1. In a rapping device, a pair of spaced heads, a vibrator body mounted between said heads, and means for supporting the device comprising a member spanning said heads and having its ends secured thereto and attaching means at an intermediate portion of said member.

2. In a rapping device, a pair of spaced heads, a jaw member on and rigid with each of said heads, a vibrator body mounted between the heads and secured thereto, a rapping member acting on both said heads, and means for suspending the device, and common means for attaching said heads to the vibrator body.

3. In a rapping device, a pair of spaced heads, an attaching jaw member provided upon and rigid with each of said heads, a vibrator mounted between the heads, a rapping member acting on both said heads and means passing through said heads and embracing the vibrator body to clamp the parts together.

4. In a rapping device, a vibrator body having a head at each end thereof, an attaching jaw member upon and rigid with each of said heads, a piston within the body acting upon both said heads, and a suspending device attached to said heads.

5. In a rapping device, a vibrator body having a head at each end thereof and bolts passing through the heads and embracing the vibrator body to secure the parts together, a hooklike jaw member attached to each end of the vibrator, a movable member within the body acting upon both said heads, and a supporting member secured to certain of said bolts to support the vibrator when out of operation.

6. In a rapping device, a vibrator body having a head at each end thereof, a movable member acting upon both of said heads, and bolts passing through the heads and embracing the vibrator body to secure the parts together, a hooklike jaw member attached to

each end of the vibrator, and a supporting member secured to certain of said bolts to support the vibrator when out of operation, one of said jaw members being adapted to be used in certain relations and the other being usable in other relations.

5 7. In a rapping device, a vibrator body having therewithin a movable reciprocable part and having upon each end thereof and in line with the moving part a hooklike jaw member adapted to support the vibrator from an object to be vibrated, said jaw members being of different types whereby the vibrator is adapted to a variety of uses.

10 15 In witness whereof, I have hereunto set my hand this 29th day of September, 1927.

GEORGE B. PICKOP.
